UNITED STATES PATENT OFFICE.

JESSE DAVID CONEY, OF WILLIAMSPORT, PENNSYLVANIA.

APPARATUS FOR CASTING METALS.

1,089,329.

Specification of Letters Patent.

Patented Mar. 3, 1914.

Application filed July 31, 1913. Serial No. 782,329.

To all whom it may concern:

Be it known that I, JESSE D. CONEY, a citizen of the United States, residing at Williamsport, in the county of Lycoming and State of Pennsylvania, have invented a new and useful Apparatus for Casting Metals, of which the following is a specification.

The invention relates to a metal casting apparatus.

The object of the present invention is to improve the construction of metal casting apparatus, and to provide a simple, inexpensive and efficient apparatus of this character of strong and durable construction designed for casting inlays, bridges, crowns, plates and other structures used in dentistry, and capable of ready adjustment to enable it to be coupled to the shaft of an ordinary dental electric motor, and adapted to utilize a rotary air compressor or pump for supplying air to a blow pipe for melting the metal to fill the mold and also for sucking the molten metal into the mold.

A further object of the invention is to equip the apparatus with means for trapping any metal, which may be drawn from the investment into the suction pipe connection and to arrange the trap at a point beyond and some distance from the investment holder in order to chill such metal and effectually prevent the same from reaching the valve for controlling the suction, and also to enable a Bunsen burner to be placed beneath the investment holder to maintain the metal at a uniform temperature while the cast is being made.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a side elevation of a casting apparatus, constructed in accordance with this invention. Fig. 2 is a front elevation of the same. Fig. 3 is a plan view. Fig. 4 is a detail elevation partly in section, illustrating the manner of adjustably supporting the rotary air compressor or pump. Fig. 5 is a horizontal sec-

tional view of the same. Fig. 6 is a vertical sectional view on the line 6—6 of Fig. 5. Fig. 7 is a detail sectional view, taken longitudinally through one of the arms of the suction pipe connection. Fig. 8 is a detail sectional view, illustrating the means for varying the supply of air delivered to the blow pipe. Fig. 9 is a plan view partly in section, showing another form of invention in which the suction pipe is provided with a single arm and investment holder.

Like numerals of reference designate corresponding parts in all the figures of the drawings.

In the accompanying drawings in which is illustrated the preferred embodiment of the invention, 1 designates a base designed to be constructed of any suitable material and provided at the back with spaced vertical rods 2 and 3, rigidly secured at their lower ends to the base and forming a stand for supporting a vertically adjustable rotary air compressor or pump 4, provided at opposite sides of its shell or casing 5 with projecting lugs 6 having vertical openings 7 through which the rods 2 and 3 pass. The rotary air compressor or pump is adapted to be adjusted vertically to enable its shaft 8 to be coupled to the shaft 9 of an electrical dental motor 10, and it is secured in its adjustment by set screws 11, mounted in threaded perforations of the lugs and engaging the vertical supporting rods 2 and 3 and clamping the rotary compressor or pump to the same. The shaft 8 of the rotary air compressor or pump is disposed horizontally and is provided with a suitable coupling member 12 to enable it to be detachably connected to the motor shaft 9, but the rotary pump or compressor may be coupled to and operated by a dental lathe or any other suitable driving or actuating device.

The shell or casing of the rotary air compressor or pump is tapered forwardly and is provided at its front wall, which is integral with the shell, with air inlet and outlet openings 13 and 14. The rear wall of the shell consists of a removable plate 15 detachably secured to the side walls of the shell. The shaft 8, which is journaled in suitable bearings of the front and rear walls of the shell, carries a forwardly tapered head 16 circular in cross section, as clearly shown in Fig. 6 and mounted eccentrically within the shell or casing 5. The rotary head 16 carries a plurality of radially arranged tapered

piston plates or blades 17, mounted in suitable recesses 18 of the rotary head and forced outwardly by coiled springs 19, which maintain the blades in contact with the inner peripheral side walls of the shell or casing. The piston plates or blades 17 extend the entire length of the shell or casing from the front to the rear walls thereof and in the rotary movement of the circular head air 10 entering the inlet port or opening 13 is forced through the outlet port or opening 14 in the usual manner, the tapered shape of the shell or casing and the rotary head facilitating a tight and proper contact of the 15 piston plates or blades with the shell or casing and an effective discharge of air from the pump or compressor.

No claim is made in the present application to the particular construction of the 20 rotary air compressor.

Extending from the air outlet port is a blow pipe connection 20, to which a blow pipe (not shown) of the usual construction is connected by a flexible tube 21, or any 25 other suitable means. The blow pipe connection 20, which is preferably tapped into the air outlet port or opening, is provided with a lateral discharge opening 22, adapted to be covered and uncovered by a slideable 30 sleeve 23, which is provided with an opening 24. The sleeve 23, which is preferably provided at the outer end with an operating flange 25, is guided on the pipe connection 20 and is held against rotary movement 35 thereon by a key 26, suitably fixed to the pipe connection and engaging an interior longitudinal groove of the sleeve. When the sleeve is at the limit of its inward movement, the lateral discharge opening 22 is 40 covered by the sleeve 23, which is adapted to be moved outwardly to carry its opening 24 into register with the opening 22, which will permit a portion of the compressed air to escape from the pipe connection 20 without 45 entering the blow pipe, thereby reducing the amount of air passing through the same.

A suction pipe connection 27 is connected with the shell or casing 5 and extends from the air inlet port or opening 13 thereof, and 50 it is equipped with a three-way valve 28 of the ordinary construction, adapted to open and close the passage through the suction pipe connection and also to connect the inner portion 29 thereof with the atmosphere 55 through a lateral port or opening 30. The three-way valve enables the air entering the rotary air compressor or pump to be drawn either through the lateral outlet 30, or through one or more arms 31 carrying investment holders so that the suction through 60 the pipe connection 27 may be utilized for drawing metal into a matrix or mold, as hereinafter fully explained. The arms 31, which extend in opposite directions from 65 the suction pipe 27, are provided with suit-

able valves 32 for closing the passages through the arms and also for enabling the air to be drawn through either of the arms. Each of the arms 31 is equipped with an investment holder but any number of such 70 arms and investment holder may, of course, be employed, or a single arm 33 may be employed, as illustrated in Fig. 9 of the drawings. When a single arm is employed, it preferably extends outwardly or forwardly 75 and forms a continuation of the suction pipe connection.

At the outer ends of the arms 31 are arranged investment holders 34 and 35 of cylindrical form and detachably mounted in 80 substantially cup-shaped bases or members 36 and 37. The investment holder 34 is of greater diameter than the other investment holder 35 for use in connection with the larger class of dental structures, and it is 85 preferably detachably secured within the cup-shaped base or member 36 by threading the parts as indicated at 38 in Fig. 2 of the drawings. The smaller investment holder 35 is preferably tapered at the lower portion at 39 to provide a tight fit. Each investment holder is equipped with a suitable handle 40 to enable it to be conveniently placed in and removed from its base or supporting member. The base or supporting 90 member of each investment holder is preferably enlarged at the bottom portion and is provided with a bore or passage 41 communicating with the interior of the cup and receiving the adjacent end of the arm or 95 branch of the suction pipe connection.

Each arm or branch of the suction pipe connection is equipped with a trap 42, consisting of a depending vertically disposed body portion secured at its upper end to the 105 suction pipe connection by a T-shaped coupling 43, or other suitable means, and having its lower end normally closed by a threaded cap 44, adapted to be readily detached to permit any contents of the trap 110 to be removed therefrom. The trap, which is adapted to catch any gold or other metal sucked through an investment, is arranged beyond and some distance from the vertical plane of the adjacent investment holder to 115 cause any molten metal drawn into the arm or branch of the suction pipe connection to become chilled before reaching the trap, so that it will positively drop into the same. Also by locating the trap at a point beyond 120 the investment holder ample space is provided beneath the same to admit of the use of a Bunsen burner for heating the cup-shaped base and the investment holder to maintain the metal at a uniform temperature. The cup-shaped bases 36 and 37 have relatively thin bottoms and the burner is adapted to be placed directly beneath the same to secure a maximum heating effect. The base 1 of the apparatus is preferably 125 130

of sufficient width to extend beneath the cup-shaped members for supporting a Bunsen burner.

In the use of the casting apparatus a mold 5 of wax is first taken, for instance, of a tooth to be inlaid or filled. The wax is suspended in an investment holder and investment material is poured around the wax pattern. The investment is allowed to set and is thor- 10oughly dried and the wax pattern is melted and drawn from the investment or matrix leaving an interior mold cavity. When it is desired to make a casting, the metal is placed in a downwardly tapered or other 15 suitable recess 45 formed in the top of the investment and communicating with the interior mold cavity by a narrow passage preferably formed by a screw or other means for suspending the wax pattern in making 20 the matrix or investment. The blow pipe is then employed to melt the metal, the air entering the rotary compressor or pump being drawn through the lateral inlet of the three-way valve. As soon as the metal is 25 brought to the proper molten condition, the valves are manipulated to cause a suction through the investment and the molten metal is drawn into the mold cavity, making a casting which is a perfect reproduction of 30 the wax pattern. After the casting is made, it is removed from the matrix or investment and finished in the usual manner.

The apparatus is equipped with an adjustable drying pan 46 mounted on the sup- 35 porting rod 3 and secured to the same by a set screw 47, as clearly illustrated in Fig. 2 of the drawings. The rod 3 is preferably extended above the rod 2 so that the drying pan, which is employed for drying large 40 investments and various other purposes, may be swung to either side of the apparatus.

What is claimed is:—

1. A casting apparatus of the class de- 45 scribed including an air compressor having an inlet opening, a suction pipe connection extending from the air inlet opening, an investment holder, means for connecting the investment holder with the suction pipe connection, and a trap depending from the 50 suction pipe connection at a point beyond

the vertical plane of the investment holder to cause any molten metal drawn from the investment holder to chill and solidify before reaching the trap, whereby such metal will positively fall into such trap, said investment holder having a base with a relatively thin bottom arranged to permit a heating device to be placed directly beneath it. 55

2. A casting apparatus of the class de- 60 scribed including a stand, a supporting base, an air compressor or pump having an inlet, a suction pipe connection extending from the air inlet and having an arm located above the base and provided with a valve, an 65 investment holder connected with the said arm and provided with a base having a relatively thin bottom and located above the stand and adapted to permit a heating de- 70 vice to be placed directly beneath it, and a 75 trap depending from the arm at a point beyond the vertical plane of the investment holder so that any metal drawn from the same will be chilled and solidified before reaching the trap and positively caused to fall into the latter.

3. A casting apparatus of the class de- 80 scribed comprising a stand having a base, a rotary pump or compressor having air inlet and outlet openings and adjustably sup- 85 ported by the said stand, a suction pipe connection extending from the air inlet opening and having a plurality of arms or branches located above the said base, each of said arms or branches being provided with a controlling valve, investment holders connected with and carried by the said arms or branches and located beyond the valves 90 thereof, and traps depending from the arms or branches and arranged at points between the investment holders and the valves of the said arms or branches. 95

In testimony that I claim the foregoing as my own, I have hereto affixed my signature in the presence of two witnesses.

JESSE DAVID CONEY.
